UNITED STATES PATENT OFFICE

MARGARET H. WITTENBERG, OF WORCESTER, MASSACHUSETTS, ASSIGNOR TO THE ROYAL WORCESTER CORSET COMPANY, OF WORCESTER, MASSACHUSETTS, A CORPORATION OF MASSACHUSETTS

CORSELET

Application filed February 15, 1932. Serial No. 593,131.

This invention relates to a corselet of that class which is of a tubular construction, having no opening, and the invention has for its object to provide a convenient garment of the class referred to which may be slipped on over the head of the wearer and which comprises brassière parts provided with means for preventing said parts from slipping up on the body of the wearer.

10 To this end the improved garment comprises sections of elastic and non-elastic fabrics which are wider at the lower part of the garment than at the top thereof. The elastic sections are preferably somewhat broader than the non-elastic sections so that they comprise somewhat more than half of the garment, rendering the same easily expandable when being put on by the wearer. An important feature of the invention consists 15 in inside elastic tapes which cross each other at the back of the garment and the ends of which are attached to the body of the garment and to the brassière parts thereof, said tapes crossing each other and sliding easily 20 through loops near the top of the back part of the garment, these crossing tapes preventing the brassière parts from slipping up on the wearer, as above stated.

In the accompanying drawings Fig. 1 is 25 a perspective view, partly broken out, looking from the back of the garment. Fig. 2 is an inside view of the back part of the garment. Fig. 3 is a cross section on lines 3-3, Figs. 1 and 2. Fig. 4 is an enlarged detail section on line 4-4, Fig. 2.

Referring to the drawings, 12 denotes sections of non-elastic fabric and 13 sections of elastic fabric. These elastic fabric sections are preferably somewhat wider than the non-elastic sections and are wider at their bottom parts than at their top parts, so that the garment is somewhat flaring downwardly. These non-elastic and elastic sections are stitched together in a well known manner.

Attached to the top of the garment are brassière sections 14 of thin material, these sections being attached at their tops and inner edges to an upward extension 12a of the front non-elastic section 12, but having free outer end parts.

Attached to the brassière sections and to the back of the garment are elastic shoulder straps 15.

Secured to the free end parts of the brassière sections 14 are crossing elastic tapes 16 at the inside of the back of the garment. Each of these tapes is attached at one end to the inside back of the garment, at 17, and the opposite end of each of said tapes is attached at 18 to a free end part of a brassière section 14. These crossing tapes slide easily through tape loops 19 stitched to the inside of the garment.

From the foregoing it will be apparent that the garment may be readily put on over the head of the wearer, the elastic sections accommodating this action, while the crossing tapes sliding through the loops 19 will enable the brassière part of the garment to accommodate itself to the movements of the wearer, as also to facilitate the adjustment of the garment to the figure of the wearer, said loops preventing the brassière parts from slipping up on the wearer.

Having thus described my invention I claim and desire to secure by Letters Patent:—

1. A tubular corselet comprising elastic and non-elastic fabric sections and front brassière parts, combined with crossing elastic tapes at the back of the garment, each of said tapes being fastened at one end to the back part of the garment and at its opposite end to a free part of a brassière part, and loops at the back of the garment through which said crossing tapes may easily slide to accommodate movements of the wearer as also to facilitate the adjustment of the garment to the figure of the wearer and prevent the brassière parts from working up on the wearer.

2. A tubular, downwardly flaring corselet comprising elastic and non-elastic fabric sections and front brassière parts, said elastic sections being wider than the non-elastic sections, combined with crossing elastic tapes at the back of the garment, each of said tapes being fastened at one end to the back part of the garment and at its opposite end to a free part of a brassière part, and loops at

the back of the garment through which said crossing tapes may easily slide to accommodate movements of the wearer as also to facilitate the adjustment of the garment to the figure of the wearer and prevent the brassière parts from working up on the wearer.

3. A tubular corselet having attached brassière parts at the front portion of its top, said brassière parts having free ends, combined with crossing elastic tapes at the back of the garment, one end of each of said tapes being attached to the body of the garment and the other end of each of said tapes being attached to a free end of a brassière part, and loops attached to the back upper part of the garment and through which said tapes may freely slide, said loops preventing said brassière parts from working up on the wearer.

In testimony whereof I affix my signature.

MARGARET H. WITTENBERG.
